(57) **CLAIM**

The ornamental design for a fishing deck for a boat as shown and described.

DESCRIPTION

FIG. 1 is a top front left perspective view of a fishing deck for a boat showing my new design;

FIG. 2 is a bottom front left perspective view thereof;

FIG. 3 is a top rear right perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged top front right perspective view of a front component thereof;

FIG. 11 is an enlarged top front right perspective view of a rear component thereof; and,

FIG. 12 is a top front left perspective view of the fishing deck for a boat of FIG. 1 shown in a condition of use.

The broken lines illustrate portions of the fishing deck for a boat which form no part of the claimed design. The broken lines depicting portions of a boat and fishing poles in FIG. 12 show environmental structure which forms no part of the claimed design.
